UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

ANTIFRICTION BEARING.

Application filed July 9, 1923. Serial No. 650,206.

To all whom it may concern:

Be it known that I, JOHN F. O'CONNOR, a citizen of the United States, residing at Chicago, in the county of Cook and State 5 of Illinois, have invented a certain new and useful Improvement in Antifriction Bearings, of which the following is a full, clear, concise, and exact description, reference being had to the accompanying drawings, 10 forming a part of this specification.

This invention relates to improvements in anti-friction bearings.

An object of the invention is to provide an anti-friction bearing, especially adapted 15 for railway cars, which bearing consists of few parts each of such design as to permit of economical manufacture, the parts being also so arranged that the anti-friction element proper is automatically self-centered 20 under the influence of gravity, when relieved of load.

The invention furthermore consists in the improvements in the parts and devices and in the novel combinations of the parts 25 and devices as herein shown and described and made the subject matter of claim.

In the drawing forming a part of this specification, Figure 1 is a vertical, sectional view taken through the ends of the body and 30 truck bolsters of a railway car showing my improvements in connection therewith. Figure 2 is a bottom plan view of the side bearing proper illustrated in Figure 1. And Figure 3 is a vertical, sectional view corresponding substantially to the section line 35 3-3 of Figure 1.

In said drawing, 10 denotes the upper portion of a truck bolster of a car and 11 the underside of the opposed body bolster. In 40 the instance shown, the improved bearing is attached to the body bolster and comprises, broadly, a retaining housing or base casting A; an anti-friction element proper B; and a pair of counter-weights C-C.

The housing A, preferably a malleable casting, is of more or less box-like form having a flat upper wall 12; curved end walls 13-13, and depending vertical side walls 14-14, each of the latter including an off-set extension 15 having vertical end walls 16-16, the latter functioning as vertical guides for the counter-weights as herein-after described. The housing A is provided with suitable lugs at its ends 17 by which 55 the housing is adapted to be riveted or

otherwise rigidly secured to the bolster. Preferably, an inserted hardened wear plate 18 is employed, the latter being entered through suitable openings in the end walls of the housing and secured to the latter by 60 rivets 19-19.

The anti-friction element B is in the form of a cylindrical roller, although the same may take other shapes as will be apparent to those skilled in the art. Said anti-friction element B is centrally cored to loosely receive a pin 19' which is entered through suitable openings 20 in the side wall of the housing before the wear plate 18 is inserted, after which, as apparent from an inspection of Figure 1, the pin 19' drops below the openings 20 and the parts thus held in assembled relation.

Two counter-weights C are employed, each of like construction. Each of said counter-weights is preferably in the form of a substantially rectangular, thick, heavy plate of such horizontal dimension as to slide smoothly between and be vertically guided by the vertical walls 16 of the lateral extensions in the side walls of the housing, hereinbefore referred to. Each of said plates is provided with a double cam groove 21, the portions of which converge upwardly to a central point as indicated at 22. Said double cam grooves loosely receive the end portions of the pin 19', as clearly indicated in Figure 3, the counter-weights being supported by said pin. In this connection, it will be understood that the extreme ends of 90 the pin 19' are, in turn, supported on the bottom horizontal edges 23 of horizontally elongated recesses 24 provided in the side walls of the housing. The counter-weights C are shown in their normal position in 95 Figure 1 and it will be obvious that the same are adapted for upward movement within the housing.

The operation of the bearing is as follows: When the anti-friction element is 100 moved to either side of central position, as for instance, toward the right as viewed in Figure 1, the pin 19' carried thereby will move in a horizontal line. As said pin so moves it is evident that it will engage the upper edges 25 of the sections of the cam recesses 21 at the righthand side of the vertical center and thereby elevate said counterweights within the housing. When 105 the load is removed from the anti-friction 110

element, the counterweights descend vertically under the influence of gravity and the upper edges of the cam recesses automatically force the pin 19' back to central position until the pin reaches the center in the double cam recesses 21. As will be obvious, this compulsory return of the pin causes the anti-friction element to be carried back simultaneously therewith, thus restoring all 10 of the parts to normal position and ready for a succeeding actuation in either direction. In this connection, it will be observed that shifting of the anti-friction element from vibration or jarring is substantially 15 completely eliminated since the anti-friction element cannot move without elevating the counter-weights and it is necessary to apply considerable power to effect the elevation of said counter-weights.

20 I have herein shown and described what I now consider the preferred manner of carrying out my invention, but the same is merely illustrative and I contemplate all changes and modifications that come within 25 the scope of the claims appended hereto.

I claim:

1. In an anti-friction bearing, the combination with a housing adapted to be secured to a bolster or the like; of an anti-friction 30 element within said housing adapted for rolling movement to either side of central normal position; a counter-weight vertically, slidably mounted on said housing and having a double cam recess therein symmetrically arranged with respect to the vertical center line thereof; and an axially disposed projection carried by and movable bodily with said element and extended within said recess whereby, when said element is 35 moved to either side of central position, said counter-weight is vertically elevated and adapted to return the element to central position when said element is relieved of load.

2. In an anti-friction bearing, the combination with a housing adapted to be secured to a bolster or the like; of an anti-friction element within said housing adapted for rolling movement to either side of normal 40 central position; a pair of counter-weights vertically, slidably mounted on said housing and located at opposite ends of said element, each of said counter-weights having a double cam recess therein symmetrically disposed with respect to the vertical center 45 line thereof; and axially disposed projections on the ends of said element, said projections being extended within said recesses and co-operable with the latter to elevate the counter-weights when said element is 50 moved to either side of central position.

3. In an anti-friction bearing, the combination with a housing adapted to be secured to a bolster or the like; of an anti-friction cylindrical roller disposed within said housing and adapted to roll to either side of central position; a counter-weight vertically, slidably mounted on said housing and having a double cam recess symmetrically arranged with respect to the vertical center line thereof; and an axially disposed projection carried by said roller and extending within said recess and co-operating with the latter to effect elevation of said counter-weight when the roller is moved to either side of central position. 65 70 75

4. In an anti-friction bearing, the combination with a housing adapted to be secured to a bolster or the like; of an anti-friction cylindrical roller disposed within said housing and adapted to roll to either side of central position therein; a pair of counter-weights each vertically slidably mounted within said housing, each of said counter-weights having a double cam recess symmetrically disposed with respect to the vertical center line of the bearing; and axially disposed projections from the ends of said roller, said projections being disposed within said recesses and co-operable with the latter to effect elevation of the counter-weights when the roller is moved in either 80 85 90 side of central position.

5. In a side bearing for railway cars, the combination with a housing adapted to be secured to the underside of the body bolster and having depending side walls, each of said side walls being provided with a horizontal ledge and a vertical guide on the inner face thereof; of an anti-friction element disposed within said housing and adapted for rolling movement to either side of central normal position therein; and a pair of counter-weights, one at each end of said element, and each vertically slidably mounted in one of the vertical guides of the housing, each of said counter-weights having a double cam recess symmetrically disposed with the vertical center line of the bearing, said element having axially extended projections at each end passing through said cam recesses and supported on horizontal ledges. 95 100 105 110

In witness that I claim the foregoing I have hereunto subscribed my name this 6th day of July, 1923.

JOHN F. O'CONNOR.
